COMBINED STEREO RECORDER AND SPEAKER HOUSINGS

Yoshihiro Masagaki, Tokyo, Japan, assignor to Sony
Corporation, Tokyo, Japan, a corporation of Japan

Filed Jan. 2, 1964, Ser. No. 78,018

Term of patent 7 years

(Cl. D26—14)

Fig. 1

Fig. 2

Fig. 3

二三一-4

FIG. 5

FIG. 1 is a front perspective view of a combined stereo recorder and speaker housings, showing my new design in a closed carrying condition;

FIG. 2 is a front elevational view;

FIG. 2 is a front elevational view;

FIG. 4 is an exploded front perspective view; and

FIG. 5 is a front perspective view thereof with the speaker housings in another position.

The dominant features of my new design are shown in solid lines in the drawing.

I claim:

The ornamental design for a combined stereo recorder and speaker housings, substantially as shown and described.
